UNITED STATES PATENT OFFICE.

PHILIP C. AUREN, OF WORCESTER, MASSACHUSETTS.

HOLDER FOR BALLS OF CROCHET COTTON.

Application filed October 3, 1923. Serial No. 666,235.

My invention relates to a holder for balls of crochet cotton, yarn and the like, and more particularly to a holder of the portable type.

- 5   Heretofore, parties doing crocheting, knitting and other similar work in which balls of crochet cotton, or yarn is employed have been greatly inconvenienced by the ball of material dropping from the lap and rolling 55 along the floor. Various holders have been devised for holding spools of thread and balls of crochet cotton or yarn. These holders have been of several types, such as to hang from the wrist or arm of the user, or 60 to clamp upon a table. The holders adapted to be supported from the wrist or arm are undesirable as the cotton or thread being drawn from the ball is liable to become tangled in the fingers and for this reason does 65 not give the free use of both arms and hands. Various other types of holders are objectionable because they are not of a light, portable construction which can be carried around in a lady's fancy work bag.
- 20   One object of my invention is to provide a holder for balls of crochet cotton that can be attached to almost any piece of furniture which has either vertical or horizontal strips having parallel faces.

- 25   Another object of my invention is to provide a support for a ball of crochet cotton or yarn that will support the ball while in use whether the ball is provided with or without a paper form in the center.

- 30   A further object is to provide a supporting member that is adjustable relative to the clamping member so that the ball of crochet cotton or yarn may be held in a vertical position regardless of whether the clamping 35 member is attached to a vertical or horizontal surface.

Further objects will be readily apparent from the following disclosure.

The drawing illustrates a perspective view

- 40   45 of my holder indicating the ball of crochet cotton in two positions thereon in dotted lines.

My holder is constructed so that the supporting member and the clamping member 50 are separable so as to insure compactness and

portability. The clamping member is preferably constructed of the celluloid jaws 10 and 11 which have a spring 12 interposed therebetween. The spring is secured to the ends of the jaws by means of the rivets 13. 55 The jaws are so shaped as to permit clamping on to the common pieces of furniture and so that the clamping faces will be as nearly parallel as possible for the average thickness of table tops, chair backs, etc.

60   The clamp jaw 10 is provided with two projections 15 and 16. The projection 15 is provided with an opening 17 to receive the end portion of a celluloid supporting member 18. The other projection 16 is provided 65 with a cut-out portion 19 to also receive the end of the supporting member 18. The opening 17 has its center line at a slight angle with the cut-out portion 19, so that when the supporting member 18 is inserted, they 70 will bind and hold it securely in position. The supporting member together with the opening 17 and the cut-out portion 19 are preferably square so that the supporting member may be inserted, having the portion 75 21 thereof either parallel with or at right angles to the clamping surfaces. This permits the part 21 to always be inserted in a vertical position regardless of whether the holder is clamped to a vertical or horizontal 80 surface.

85   The supporting member is so shaped that the portion 22 is, in any position relative to the clamping member, substantially parallel with said clamping members. This is particularly adapted to support balls of crochet cotton or yarn having no supporting centers, where the yarn is withdrawn from the center of the ball, the outer portion of the ball remaining intact until nearly the outer 90 layer is reached. This portion also serves to support balls of crochet cotton in which the paper centers have fallen out or have been removed.

95   The celluloid jaws 10 and 11 are provided with felt protection pads 24 and 25 to prevent the clamping member from marring highly polished pieces of furniture to which it might be clamped.

Having thus described my invention, what 100

I claim as new and desire to secure by Letters Patent is:

A holder for balls of crochet cotton comprising a substantially U-shaped spring, a pair of clamping jaws having one end of each jaw fixed to the ends of said spring, and extending so that the other end of each jaw

projects beyond the closed end of said spring, a supporting member and projections on one of said clamping jaws adjacent the spring end to detachably hold said member.

Signed at Worcester, Massachusetts, this 1st day of October, 1923.

PHILIP C. AUREN.
